INVENTOR.

John Alexander,
BY
Arthur B. Jenkins,
ATTORNEY.

UNITED STATES PATENT OFFICE.

JOHN ALEXANDER, OF HARTFORD, CONNECTICUT.

RADIATOR.

1,109,384.

Specification of Letters Patent. Patented Sept. 1, 1914.

Application filed May 12, 1912. Serial No. 786,290.

To all whom it may concern:

Be it known that I, JOHN ALEXANDER, a citizen of the United States, and a resident of Hartford, in the county of Hartford and State of Connecticut, have invented a new and Improved Radiator, of which the following is a specification.

My invention relates to the class of devices employed more especially as cooling devices and particularly in connection with automobile construction, and an object of my invention, among others, is to provide a device of this class that shall embody extreme simplicity in its construction and, at the same time a high degree of efficiency in its operation.

One form of device embodying my invention and in the construction and use of which the objects herein set out, as well as others, may be attained, is illustrated in the accompanying drawings, in which—

Figure 1 is a view in front elevation of a radiator embodying my invention, with parts cut away in vertical section to show construction. Fig. 2 is an edge view of the radiator, with parts broken away to show construction. Fig. 3 is a detail view showing the construction of one of my improved radiator tubes and the means for securing it to a plate of the radiator, (scale enlarged).

In the accompanying drawings the numeral 5 denotes the reservoir located at the top and 6 the chamber located at the bottom of a radiator of common and well known construction, these two parts being connected at each end by a series of pipes 7, each series consisting of any desired number of pipes.

The numeral 8 denotes the pipe communicating with the reservoir 5, and 9 that with the chamber 6, these pipes being arranged for connection with the water jacket of an engine, all of which may be of ordinary and well known construction.

In the construction of devices of this class it is of material advantage to secure the parts, as far as possible, without solder, or like material, and my improved radiator contemplates such a structure in which the air is directed on to the engine by means of tubes extending through or into the radiator structure.

In carrying my invention into effect I provide a number of tubes extending between the front and rear plates 10—11, respectively, of the radiator, these tubes being

preferably located so that the openings thereto shall be very closely associated on the front plate. Each of these tubes 12 is of any suitable size in diameter and is 60 threaded as at 13 at one end to receive a flanged or threaded nipple 14, the flange 15 of which rests against the outer surface of the plate and clamps the plate between the end of the tube 12 and the flange 15. The 65 radiator structure is of such rigidity, and the means for securing the tubes to the front plate are so effective, that these tubes may be loosely engaged in the openings in the rear plate 11, and without securing means 70 therefor, or, if it be desired, any means, (solder or similar material being preferably excepted) may be employed for securing the tubes to the rear plate.

As the radiator is moved through the air, 75 currents are forced through the tubes 12 on to the engine, and in order that these currents of air shall meet with as little resistance as possible, and shall be unimpeded in their progress, each nipple is provided 80 with a relieved or bell shaped outlet 16 so that air entering the flared mouth 17 of each nipple is impeded to a minimum degree, the column of air taking its natural form, the relieving and cutting away of the nipple at 85 the back also preventing any eddies or back flow of air and also preventing cross currents from interfering with each other so that substantially all of the resistance that exists to the flow of air through the pipe is 90 imposed by the friction.

The tubes 12 hereinabove described extend from the front to the back plate at that part of the radiator not occupied by the pipes 7, and short tubes 18 are secured to the 95 front plate by the nipples 14 in the manner above described, these tubes being shortened to permit their location to direct the currents of air on to and about the pipes 7, but other than the shortening of these tubes the 100 construction is exactly as above described with respect to the tubes 12.

While I have shown and described herein a preferred form of construction for carrying my invention into effect, this may be 105 departed from to a greater or lesser degree within the scope of the appended claims and yet be within the spirit and intent of the invention.

It is an aim of my present invention to so 110 shape the interior of the nipple to conform to the shape that will naturally be assumed

by a column of air entering the tube 12, that the presence of the nipple shall not reduce the amount of air that would otherwise pass into the tube and to flare the mouth to 5 an extent to increase the amount of air that would otherwise pass into the tube.

I claim—

1. In a radiator, a frame including a front and back plate, and a series of tubes having 10 screw-threaded ends and connected with one of said plates, the connections including nipples fitting within said screw threaded ends of the tubes and having openings with flared outlets at that end of the nipples opening 15 into said tubes.

2. A radiator including a frame having front and back plates, and a series of tubes, having screw-threaded ends, said tubes extending between said plates, and being 20 secured to one of the plates to deliver air through the openings in said tubes, the con-

nections for said tubes including nipples fitting the screw threaded ends of the tubes and having flared mouths at one end and flared outlets at the opposite ends that open 25 into said tubes.

3. A radiator including a frame having front and back plates with a reservoir at the top of the frame and a chamber at the bottom connected by circulating pipes, and 30 a series of tubes having screw threaded ends connected to the front plate and opening in line with said pipes, the connections securing the tubes to the place including nipples fitting said screw threaded ends of the tubes 35 and having flared mouths at their inlet ends and flared outlets at the opposite ends of the nipples that open into said tubes.

JOHN ALEXANDER.
